UNITED STATES PATENT OFFICE.

ALFRED MINNICK, OF NEWARK, NEW JERSEY.

TRAIN-CONTROL SYSTEM.

1,226,792.

Specification of Letters Patent. Patented May 22, 1917.

Application filed October 10, 1916. Serial No. 124,821.

To all whom it may concern:

Be it known that I, ALFRED MINNICK, a citizen of the United States of America, residing at Newark, in the county of Essex, 5 State of New Jersey, have invented certain Improvements in Train-Control Systems, of which the following is a description, reference being had to the accompanying drawings, forming a part thereof.

10 The object of the invention is to provide a system of train signaling and control mechanism whereby abnormal conditions in any respect will be indicated to the operator, and in case of his inattention, whether voluntary or unavoidable, will involve the 15 checking of the speed or the stopping of the train, and also of giving periodic signals indicating safe or doubtful conditions, or possible danger ahead, requiring the exercise of 20 caution.

Further objects and advantages of the invention, will appear in the following description of a preferred embodiment, it being understood that changes in the form, 25 proportion and minor details may be resorted to within the scope of the appended claims without departing from the spirit of the invention.

In the drawing,

30 Figure 1 is a general diagrammatic view of the system.

Fig. 2 is a plan view of a series of stationary or track magnets.

Fig. 3 is a cross-sectional view of a road- 35 bed showing the arrangement of magnet series with reference to the track-rails.

Fig. 4 is a view of a form of traveling armature and connections arranged in operative relation with the stationary or track 40 magnets.

Fig. 5 is a plan view of a set of armatures for control by track impulses.

The invention contemplates, generically, 45 a system of normally energized track or stationary magnets, arranged in series in track blocks or sections, to be determined as to location and length by topographical and traffic conditions, with relation to track-rails or other conductors in different blocks 50 or sections whereby "shorting" or "grounding" of the energized circuits may be effected by rolling stock, in combination with moving or traveling armatures, carried in the fields of said magnets, by the locomotives, tenders, cars or other elements of the 55 rolling stock, and disposed in influenced re-

lation with devices adapted for making partial or complete application of brakes, for giving periodic clear or safe signals, for giving successive caution and danger or stop signals in the engine cab, and for actuating recording mechanism as to the character of indication, or signals and the like means also being employed for effecting track or road-side signals, when considered necessary or 60 desirable.

In the embodiment of the invention illustrated herein the track rails 10 are shown divided into blocks or sections, A. B. C. D. E., B. C. D. E., each block being equipped 70 with a series of stationary or road magnets 11, arranged in circuit with batteries 12, or other sources of electrical energy, which may, as shown, be arranged in circuit with suitable road-side or track signals.

As all of the circuits are identical in arrangement, it will be necessary to trace but one in detail for the purpose of illustration, and the block A, having its track rails 10 connected with battery 12, will be used as a 80 basis of description, with said rails in a circuit defined by the heavy dotted lines x, and including magnet 13, the upper section or member of a double solenoid 14, an armature 15 and contact 15^a, the lower section 85 or member of the double solenoid 16, a series of "caution" track magnets 11^a in block D, the "danger" track magnets 11 in blocks C and C', "caution" track magnets 11^a in block D, the lower section or member of the 90 double solenoid 17, the contact 18^a and armature 18, the upper section, or member of double solenoid 19^a and the magnet 20. When the block A is occupied, as shown by the track wheels 21, the circuit just described is "grounded" or "shorted" thereby deenergizing magnet 13 and the upper section or member of the double solenoid 14, giving a "danger" road-side signal in block 95 C, deenergizing the lower section or member of double solenoid 16, (giving a "caution" road-side signal in block D), deenergizing "caution" track magnets 11^a in blocks D and D' and "danger" track magnets in blocks C and C', and setting the road-side 100 signals in relation thereto.

The double solenoids above mentioned are designed to operate road-side signals or semaphores, under such conditions that the energization of both sections or members of 110 a double solenoid will hold the signal at "clear," the deenergization of one member

will hold the signal at "caution," while the deenergization of both sections or members will permit the movement of the signal to "danger," a weight, or other equivalent positive actuating means, being employed to oppose the action of the solenoid and insure a caution or danger signal in the event of any failure of the circuits, due to the proximity of a train or inoperativeness of any of the related elements.

Carried in the fields of the track magnets, as by the engine, tender, or other element of the rolling stock, are the traveling armatures 23, and 24, the former in relation to the danger or "stop" magnets and the latter in relation to the side or "caution" magnets an additional caution armature being employed if necessary as indicated in Fig. 5, to permit of movement of the rolling stock on the track in either direction without duplicating the track equipment.

These armatures may be of any preferred construction suitable for energization by the track magnets, and adapted for movement, or for controlling the movement of the other dependent elements, when deenergized or released from the influence of their respective track magnets, and each, as illustrated, consists of a shoe, of a length sufficient to bridge the interval between two adjacent track magnets in normally arranged series, so as to receive the influence of one before passing beyond that of another in the same series, with, for example, a resisting spring 35 for moving the shoe to an active position,—that is, a signal-giving or brake applying position when released from the influence of the track magnets.

In order that distinctive signals may be given, or brake applying means partial or complete may be operated the shoe constituting the armature is movably mounted for attractive influence by the track magnets, while at the same time being supported by suitable hangers, which permit of rearward displacement in the event of encountering an unusual obstacle on the road-bed, the pivotal movement of the armature being such as to open normally-closed signal circuits or brake applying circuits, to effect without the intervention of the engineer that control which is necessary in order to insure safety.

Inasmuch as the specific cab mechanism relating to the signaling and train checking or stopping devices form no specific part of the present invention, it has been deemed sufficient merely to show contacts affected by the shoe or armature or the position of the latter, whereby the relations of the parts are altered when the conditions of the circuit or circuits of the track system may be changed in accordance with the proximity of rolling stock.

In order that this relation may be more

fully understood, attention is called to the fact that when, for example, a train enters the block A thereby grounding or shorting the circuit through the battery energizing the track rails of that circuit, the magnets 70 in block C and in block C' respectively in advance and in rear of the train, are deenergized so as to give a danger or stop signal to any train approaching in the opposite direction or following that of the train 75 in question, while in blocks D and D' the caution magnets are deenergized so as to influence the caution armature of any approaching train either in the opposite direction or following that of the train affecting 80 said circuit, to give a caution signal and, if preferred, a partial or gradual application of the brakes so as to reduce the speed of the train without voluntary intervention of the engineer or other operative. 85

Another condition which is contemplated in this system is that of giving a definite and positive and "clear" signal on the entrance of a train to each block, or at such intervals as may be deemed necessary, according to the traffic conditions. In this connection, for example, it is desirable to give a "clear" signal on approaching a curve or a draw-bridge or the like, even when it is not necessary to signal definitely on the entrance to a block on a "clear" or straight track. In order that this may be accomplished, one, two or more magnets may be omitted at the point where the signal is desired, so that the armature or shoe is momentarily de-magnetized, it being preferable to use laminated material in order that the negative influence may be prompt and to employ a supplemental armature or switch 105 arranged within the field of influence of the main armature or shoe, so that it may be promptly influenced by the de-magnetization of the armature or shoe, said supplemental armature or switch being arranged to control circuits effecting "clear" signals 110 either audible or visual. In the same way, the omission of a suitable number of magnets in a block circuit at the approach to a curve, a bridge, a trestle or other dangerous point of a road may by the de-magnetization of 115 the armature affecting a mechanism designed to produce a partial reduction of pressure, for example, in an air brake system, making a partial application of the brakes so as to reduce the speed of the train to that which 120 will enable it to proceed safely, whether the engineer is attentive or not.

In illustrating the system so as to include load-side signals, and maintain conditions therein which correspond respectively with 125 those existing in the track magnets of the several blocks, while securing a progressive setting and resetting or restoring of the said signals as a train proceeds, such operations taking place in reverse order in front and 130

in rear of the advancing train, there is incorporated a series of relay circuits including batteries or other energizing elements controlled by the magnets 13 which are included in the main or track circuit and actuate armatures 15, 18, constituting switches or circuit breakers. The double solenoids are so constructed that when both upper and lower coils are energized, the armature thereof 6 is held down to the limit of its movement to maintain the semaphore or other signal to indicate "safe;" if the lower coil is de-energized, the armature is permitted to rise, under the influence of a weight or other element of the semaphore, to indicate "caution," being held in that position by the upper coil; and if both coils are deenergized, the signal is permitted to indicate "danger."

It will be obvious from the foregoing that 20 under the control of the system herein outlined, the possibilities of train control and signaling, both as to the cab and the roadside are practically unlimited, depending entirely upon the wiring and the efficiency 25 of the train checking and stopping devices, and that the efficiency of the system is independent of the human equation.

What is claimed is:

1. A train signal and control system having 30 a track-circuit adapted to be grounded by rolling stock and having included therein stationary track magnets in series extending substantially throughout a different block from that in which the ground may be effected, in combination with a traveling train-carried armature disposed in the field of said magnets.

2. A train signal and control system having 40 a normally-closed track-circuit adapted to be grounded by rolling stock and having included therein stationary track magnets arranged in series extending substantially throughout one block, and track rails in another block, in combination with a traveling train-carried armature disposed in the field of said magnets.

3. A train signal and control system having 50 a track-circuit adapted to be grounded by rolling stock, and having included therein stationary track magnets in series in a different block from that in which the ground may be effected, in combination with a traveling train-carried armature disposed continuously in the field of one or more of 55 said magnets.

4. A train signal and control system having a track-circuit adapted to be grounded by rolling stock, and having included therein stationary track magnets arranged in parallel series in successive blocks separated 60 from that in which the ground may be effected, in combination with traveling train-carried armatures disposed in the fields respectively of said series of magnets.

5. A train signal and control system having a track-circuit adapted to be grounded by rolling stock, and having included therein stationary track magnets arranged in series in a different block from that in which the ground may be effected, in combination 70 with a traveling train-carried armature disposed in the field of said magnets, and of a length at least equal to the interval between the fields of adjacent magnets.

6. A train signal and control system having 75 a track circuit adapted to be grounded in one block by rolling stock, and having included therein stationary track magnets arranged in series extending substantially throughout another block, a traveling train-carried armature moving in the field of said magnets, and train control apparatus actuatable by said armature.

7. A train signal and control system having 80 a track-circuit adapted to be grounded in one block by rolling stock, and having included therein stationary track magnets arranged in series extending substantially throughout another block, a traveling train-carried armature moving in the field of said 85 magnets, and signaling mechanism actuatable on de-magnetization of said armature.

8. A train signal and control system having 90 a track circuit adapted to be grounded in one block by rolling stock, and having included therein stationary track magnets arranged in series extending substantially throughout another block, a traveling train-carried armature moving in the field of said 95 magnets, and train checking and signaling 100 mechanisms actuatable on variations of magnetization of said armature.

This specification signed and witnessed this 3 day of October A. D. 1916.

ALFRED MINNICK.
